UNITED STATES PATENT OFFICE.

JOSEPH E. BATIE, OF DETROIT, MICHIGAN, ASSIGNOR TO KELSEY WHEEL COMPANY, INC., OF DETROIT, MICHIGAN, A CORPORATION OF NEW YORK.

RIVETING MACHINE.

Application filed June 20, 1921. Serial No. 478,868.

To all whom it may concern:

Be it known that I, JOSEPH E. BATIE, a citizen of the United States of America, residing at Detroit, in the county of Wayne 5 and State of Michigan, have invented certain new and useful Improvements in Riveting Machines, of which the following is a specification, reference being had therein to the accompanying drawings.

10 The invention relates to riveting machines and is designed for use particularly in riveting cleats upon tractor wheel rims.

In the usual construction of tractor wheel, 15 the cleats extend diagonally of the rim or at an angle relative to the plane of rotation thereof, and these cleats are secured to the rim by several rivets. Heretofore, the cleats have been secured to the rims either by manually riveting the same or by riveting in a machine in which each of the rivets 20 for each cleat is individually operated upon to form its head. These methods are objectionable, first, because of the length of time required to rivet the cleats upon the 25 rim, and second, because the base flanges of the cleats may not be in contact with the face of the rim throughout their length.

This latter objection is due to the fact that the base flanges of the cleat may not contact 30 with the face of the rim throughout their length when placed thereon, and consequently when the hot rivets are individually operated upon to form their heads, they are very liable to bulge out in the space between 35 the base flange of the cleat and the face of the rim, and as a consequence, the rivet head is weakened and the base flange of the cleat is held out of contact with the rim face.

With my construction, these objections are 40 avoided by first clamping the base flange of the cleat against the rim face and then simultaneously operating upon all of the rivets securing the cleat to the rim to form their heads.

45 Other objects of the invention are to provide a riveting machine in which the horn carrying the rim is pivotally mounted at one end upon the frame, whereby the horn is permitted to swing so that a rim may 50 be readily positioned thereon or removed therefrom, and also may be readily revolved thereon to a desired position for riveting the succeeding cleat; and to provide a riveting machine in which the rivet snaps for forming the heads upon the rivets will engage

the ends of the rivets to exert pressure thereon in substantially the correct direction to form substantially accurate heads. Further objects of the invention reside in the novel features of construction and combinations 60 and arrangements of parts as more fully hereinafter set forth.

In the drawings:

Figure 1 is a front elevation of a machine embodying my invention and diagrammatically showing the pipe lines and valves controlling the operation of the machine;

Figure 2 is a side elevation thereof in which the pipe lines and valves controlling the operation of the machine are also dia- 70 grammatically shown;

Figure 3 is a perspective view of the machine omitting the pipe lines and valves;

Figure 4 is a vertical cross section through the lower end of the machine;

Figures 5 and 6 are respectively, a top plan view and an end view of the horn;

Figure 7 is a top plan view of the pad upon the horn;

Figures 8 and 9 are respectively cross sections on the lines 8—8 and 9—9 of Figure 7.

The frame of the riveting machine comprises the parallel sides 1 and 2, the upper cross bars 3 and the lower cross bar 4. The frame is suitably suspended by means (not shown) connected to the upper cross bars 3.

5 5 is a horn which is connected at one end to the frame side 2 by the horizontal pivot 6 which permits the horn to swing through a path parallel to a vertical plane. The other end of the horn has the gudgeon 7 which is adapted to be engaged by the bearing 8

10 at the lower end of the support 9, the upper end of this support being rotatably and longitudinally slidably mounted upon the gudgeon 10 which forms part of the lower cross bar 4 and extends through the frame side 1. 11 is a pad which is carried upon the horn 5 and has extending longitudinally

95 thereof, the convex face 12 of substantially the same radius as that of the wheel rim 13. Since the cleats 14 are arranged diagonally upon the face of the rim and since it is desirable to have the row of rivets 15 ex-

100 tending parallel to the axis of and above the horn 5, the longitudinal axis of the pad 11 is arranged at such an angle to the longitudinal axis of the horn 5 that the row of rivets 15 for securing the cleat to the rim

105 will extend parallel to the axis of and above

110

the horn 5 when the rim is mounted upon the pad.

In the method of riveting a cleat 14 to the rim 13 the cleat with the hot rivets 15 extending through apertures in the base flange 16 of the cleat is placed upon the rim 13 so that the lower ends of the rivets will extend through apertures previously formed in the rim. The heads at the outer ends of the rivets and engaging the outer face of the base flange have been previously formed so that the rivets are suspended upon the base flange.

To clamp the base flange 16 of the cleat 14 firmly against the rim 13 and to simultaneously form heads upon the inner ends of the row of rivets 15 to secure the cleat to the rim, I have provided the following construction:

20 17 is a cylinder suspended from the horn 5. 18 is a piston rod extending from the lower end of the cylinder 17 and having at its lower end the enlargement 19. 20 are rods extending through lugs 21 and 22 upon 25 opposite sides of the horn, 5, these rods being connected to the enlargement 19 and to the pad 11. The piston in the cylinder 17 is adapted to be raised by means of compressed air entering through the pipe 23 and controlled by the valve 24, which latter has the operating handle 25 adapted to be actuated by the foot pedal 26. 27 are cylinders arranged in staggered relation and 30 pivotally suspended from the upper cross bars 3 of the frame, there being the same number of cylinders as rivets 15 (in the present instance 4). Extending through the lower end of each cylinder 27 is the piston rod 28 which is pivotally connected to the outer end of a bell crank 29. This bell crank has the hub portion 30 which is journalled upon the shaft 31 extending between the frame sides 1 and 2 and the bell crank has the depending arm 32 which is pivotally secured to the bifurcations 33 at the upper end of a link 34. The lower end of this link has the bifurcations 35 which are pivotally connected to a plunger 36 which longitudinally slidably engages in a suitable bearing in the lower cross arm 4 of the frame. The lower end of this plunger 36 is provided with a rivet snap 37 having a recess in its lower face for engaging the formed head upon the upper end of the hot rivet 15. In alignment with this rivet snap 37 is a corresponding rivet snap 38 having a recess in its upper face for forming the head upon the lower end of a rivet 15. The rivet snap 38 slidably engages in the pad 55 11 and is mounted upon the horn 5. To adjust the height of this rivet snap so that its upper face will extend the proper distance above the convex face 12 of the pad when the latter is in its lowermost position, 60 there is the set screw 39 threadedly engag-

ing in the horn 5 and adapted to engage the lower end of the rivet snap.

The pistons in the cylinders 27 are also adapted to be actuated by compressed air which enters the cylinders through the pipes 70 40 and is controlled by the four-way valve 41 having the operating handle 42.

In operation when the rim 13 has been correctly positioned upon the pad 11 and the cleat 14 with the hot rivets, 15 extending through its base flange 16 has been positioned upon the rim with the lower ends of the hot rivets extending through the previously formed apertures in the rim, the foot pedal 26 is depressed to open the valve 80 24 to allow compressed air to enter the cylinder 17 and raise the piston therein, thereby, raising the pad 11 through the rods 20 and piston rod 18. The raising of the

pad 11 clamps the base flange 16 of the cleat 14 against the face of the rim 13. The next operation is the opening of the four-way valve 41 to allow compressed air to enter the cylinders 27 through the pipes 40 so

that the pistons in these cylinders are simultaneously forced downwardly and longitudinally move the plungers 36 with their rivet snaps 37, as well as the pad 11, downwardly by means of the piston rods 28, bell

cranks 29, and links 34. One of the piston rods 28 upon its downward movement engages the extension 43 of the operating rod 25 of the valve 24 to shut off the supply of compressed air to the cylinder 17 and to permit of its escape from the cylinder, the air in the cylinder 17 having been further compressed by reason of the downward movement of the pad 11 actuated by the plungers 36. Thus upon continued downward movement of the plungers 36 with

their rivet snaps 37, the pad 11 moves downwardly therewith and permits of the lower ends of the rivets 15 finally coming in contact with the rivet snaps 38 carried upon the horn 5 to form heads upon the lower ends. To

clamp the base flange 16 of the cleat against the face of the rim upon releasing of the air pressure in the cylinder 17, there are coil springs 44 for yieldably holding the pad 11 in its upper position. These coil springs surround the rods 20 and abut against the lower lugs 21 upon the horn 5 and against

collars 45 upon the rods.

For the purpose of correctly forming the heads upon the lower ends of the rivets 15, the axes of the outer apertures in the pad 11 and in which the rivet snaps 38 slidably engage, are inclined as shown particularly in Figures 8 and 9, the angle of inclination being substantially four degrees from vertical. Also the direction of movement of the outer rivet snaps 37 mounted in their respective plungers 36 are correspondingly inclined. With this arrangement, the different degrees of inclination of the rivets 15

130

relative to each other are taken care of. The reason for the different degrees of inclination of the rivets relative to each other is that each rivet extends radially of the rim 5 but is offset from the others peripherally of the rim.

Since the weight of the horn 5 with the pad 11 and its actuating mechanism is considerable, I have provided power means for 10 swinging the horn. In detail, 46 is a cylinder pivotally mounted upon the frame side 2 at 47. 48 is a piston rod extending through the outer end of the cylinder 46 and pivotally connected to the bracket 49 rigidly secured at its lower end to the pivoted end of the horn. The piston in the cylinder 46 is adapted to be actuated by compressed air which enters through the pipe 50 and is controlled by the valve 51 having 20 the actuating handle 52. Thus, with this construction when it is desired to lower the horn from the position shown in full lines in Figure 1, the support 9 is moved longitudinally upon the gudgeon 10 to the position indicated by dotted lines when the horn is free to swing downwardly. To raise the horn, the valve 51 is opened which permits air to enter through the pipe 50 into the cylinder 46 and force the piston rod 48 outwardly, which through the bracket 49 swings the horn 5 upwardly so that its gudgeon 7 is in position to be engaged by the bearing 8 of the support 9.

To position the horn in its raised position, the same is preferably provided with the projection or pin 53 near its free end which is adapted to engage in a correspondingly shaped recess in the lower end of the frame side 1.

40 It will also be noted that the lower cross bar 4 of the frame has the gudgeon 54 extending through the frame side 2 and engaging in the bracket 55 which latter has the pivot portions 56 and 57 respectively for 45 the pivots 6 and 48. This bracket is secured against the frame side 2 by suitable means such as the stud bolts 58.

What I claim as my invention is:

1. In a machine for riveting one member to another, the combination with a movable plunger, of a horn, a pad movably mounted upon said horn to clamp the members against said plunger, a rivet snap mounted upon said horn and freely engaging in said pad and adapted to extend beyond the outer face thereof when said pad is in one position of adjustment, means for moving said pad from said position of adjustment toward said plunger to clamp the members therebetween, and means for moving said plunger toward said rivet snap and for moving said pad therewith to rivet the members to each other.

2. In a machine for riveting one member 65 to another by a series of rivets, the combina-

tion with a series of plungers, of a support movable toward said plungers to clamp the members therebetween, a series of rivet snaps freely movable in said support and adapted to form heads upon corresponding ends of the rivets, means for moving said support toward said plungers to clamp the members therebetween, and means for subsequently simultaneously moving said plungers with said support toward said rivet 75 snaps to form heads upon corresponding ends of the rivets.

3. In a machine for riveting a diagonally arranged cleat to a rim with a series of rivets, the combination with a series of plungers substantially in alignment with each other, of a series of rivet snaps, the axes of said rivet snaps being inclined relative to each other, and the directions of movement of said plungers being also inclined relative 80 to each other to compensate for the peripheral offsetting of the rivets relative to each other about the rim, whereby the heads formed upon the rivets will be substantially correct.

4. In a machine for riveting one member to another, the combination with a suspended frame having sides and upper and lower cross bars, of a horn pivotally mounted at one end to one of said sides, means upon the other of said sides for engagement with the free end of said horn to hold the same in one position of adjustment, and a plunger slidably engaging in said lower cross arm and adapted to move toward said horn.

5. In a machine for riveting one member to another, the combination with a frame having sides, and upper and lower cross bars, of a cylinder pivotally suspended from said upper cross bar, a piston rod extending through the lower end of said cylinder, a bell crank rotatably mounted upon said sides and having one arm pivotally connected to said piston rod, a plunger slidably mounted in said lower cross bar, and a link pivotally connected to the upper end of said plunger and to said bell crank.

6. In a riveting machine, the combination with a frame, of a horn pivotally mounted upon said frame, and a pivotally mounted power device for swinging said horn in one direction.

7. In a riveting machine, the combination with a frame, of a horn pivoted to said frame at one end and adapted to swing through a path substantially parallel to a vertical plane, means upon said frame engageable with the free end of said horn for holding the same in a predetermined position, and pivotally mounted power actuating means for swinging said horn in one direction.

8. In a riveting machine, the combination with a frame, of a horn pivoted at one end to said frame and adapted to swing through

a path substantially parallel to a vertical plane, a bearing upon said frame adapted to engage the free end of said horn to hold the same in a predetermined position, a cylinder pivoted upon said frame, and a piston within said cylinder connected to said horn to swing the same in one direction.

9. In a machine for riveting one member to another, the combination with a frame having sides and upper and lower cross bars, of a horn pivotally mounted at one end upon one of said sides, a support upon the other side detachably engaging the free end of said horn, a cylinder mounted upon said horn, a pad above said horn, a piston within said cylinder and connected to said pad to raise the same, a second cylinder carried by said upper cross bar, a plunger movable toward said horn, a piston within said second cylinder connected to said plunger for actuating the same, a valve controlling the operation of the piston in said first-mentioned cylinder, a second valve controlling the operation of said piston in said second cylinder, and means for automatically actuating said first-mentioned valve to release the motive force in said first-mentioned cylinder upon actuation of said second-mentioned piston.

10. In a riveting machine, the combination with a frame, of a horn mounted thereon, a plunger also mounted thereon, a pad movable toward said plunger, means for moving said pad toward said plunger, a rivet snap mounted upon said horn and freely engaging said pad in alignment with said plunger, means for moving said plunger toward said snap and said pad therewith, and means for yieldably resisting movement of said pad with said plunger.

11. In a riveting machine, the combination with a frame having sides and a cross bar, said cross bar being provided with a

gudgeon extending through one of said sides and beyond its outer face, of a horn pivotally mounted at one end upon the opposite side of said frame, and a support slidably mounted upon said gudgeon and having a bearing for engagement with the free end of said horn.

12. In a riveting machine, the combination with a frame having sides and a cross bar, said cross bar being provided at one end with a gudgeon extending through one of said sides, of a bracket upon said gudgeon, a horn pivoted to said bracket, a cylinder also pivoted to said bracket, and a piston in said cylinder connected to said horn to swing the same.

13. In a machine for riveting one member to another, the combination with a movable plunger, of a support, a pad carried upon said support and carrying said members to be riveted to each other, a rivet snap secured to said support, means for moving said pad toward said plunger to clamp said members to be riveted to each other, and means for moving said plunger and pad toward said support and rivet snap to effect the riveting operation.

14. In a machine for riveting one member to another, the combination with a movable plunger, of a support, a pad upon said support for carrying said members to be riveted to each other with their securing rivet, a rivet snap upon said support, means for moving said pad toward said plunger to bring the rivet into contact with said plunger and to also clamp said members to be riveted to each other, and means for moving said plunger and pad with said members to be clamped to each other toward said support and rivet snap to bring the opposite end of said rivet into contact with said rivet snap.

In testimony whereof I affix my signature. JOSEPH E. BATIE.
